UNITED STATES PATENT OFFICE.

GEORGE A. BALZ, OF RAHWAY, NEW JERSEY.

COKE OVEN OR CARBONIZING FURNACE.

Application filed July 6, 1917. Serial No. 178,888.

To all whom it may concern:

Be it known that I, GEORGE A. BALZ, a citizen of the United States of America, residing in Rahway, in the county of Union 5 and State of New Jersey, have invented certain new and useful Improvements in Coke Ovens or Carbonizing Furnaces, of which the following is a specification.

This invention relates to apparatus for 10 carbonizing coal, garbage, wood and other materials, and for the production of coke, charcoal, gas, and their by-products.

According to this invention the carbonizing furnace is constructed as a vertical furnace in cylindrical or annular form, with a 15 multiplicity of carbonizing chambers or retorts which, with their heating chambers and regenerators, are arranged to form sectors of an upright cylinder, or other closed 20 figure.

The oven is shown in the accompanying drawings, wherein,—

Figure 1 is a vertical mid-section;

Fig. 2 is a horizontal section, the left half 25 in the plane of the line 2 in Fig. 1, the upper right-hand quarter in the plane of the line 2', and the lower right-hand quarter in the plane of the line 2'';

Fig. 3 is a horizontal section, the left-hand 30 half being in the plane of the line 3 in Fig. 1, and the right-hand half in the plane of the line 3' therein;

Figs. 4 and 5 are horizontal sections 35 through the base of the stack in the planes of the lines 4-4 and 5-5 respectively in Fig. 1;

Fig. 6 is a fragmentary vertical section, being an enlargement of part of Fig. 1;

Figs. 7, 8 and 9 illustrate a modification of 40 the stack base, Fig. 7 being a vertical mid-section and Figs. 8 and 9 horizontal sections on the lines 8-8 and 9-9 respectively in Fig. 7.

Fig. 10 is a fragment of Fig. 1, showing 45 the application of means for use in making water gas:

Referring first to Fig. 1, A designates the base or foundation on which the structure is erected. B B illustrate a steel framework 50 for supporting the carbonizing oven or furnace proper, comprising a platform C of iron plates resting upon girders. The masonry structure D is built up on this platform and has externally the form of an upright cylinder or other closed figure. It has a central steam flue E and an outer wall F,

between which the interior of the oven is divided by radial partitions G into sectors of any convenient number (eight being shown), it being desirable, but not necessary, 60 that the number of sectors shall be an even number. In each sector is formed a carbonizing chamber or retort H (these being hereinafter called retorts). These retorts are flanked on the sides toward the center 65 and toward the circumference, respectively, by heating chambers or flues which for the even-numbered sectors are lettered I, J respectively, and for the intervening odd-numbered sectors are lettered I', J'. In each 70 sector are two regenerating chambers, one, K, between the heating flues I or I' and the center, and the other, L, between the heating flues J or J' and the external wall. These several chambers and flues are formed in the building up of the structure. The structure may be made of any material suitable to the 75 temperatures required for the distillation or carbonization to be performed; for coking it should be of masonry, with those parts subjected to high temperatures made of or lined with fire brick or other suitable refractory.

Each retort H is closed at its bottom by a plug or door M, and at its top has an upright flue N through which the gases distilled off from the coal or other carbonizable material may ascend, this flue being continued by a pipe N' leading to suitable gates O O' which communicate with hydraulic or gas-collecting mains P and P', 90 these latter being annular so as to receive the gaseous products from all of the retorts. The purpose of two hydraulic mains is that by proper manipulation of the gates O O' in the well-known manner the lighter products first distilled off may be discharged 95 into one hydraulic main, and the heavier products later coming off may be directed into the other one.

The bottom doors or closing plugs M are 100 fastened in place during the carbonizing in any suitable way, and are provided with any suitable means for lowering them and moving them out of the way when it is desired to dump out by gravity the carbonized charge from the retort. At such time the charge falls into a quenching vessel Q, which may contain water, or into which water may be sprayed. The top of the vessel Q is closed by a cover Q' made 110 in sections, one of which, Q², is shown withdrawn in Fig. 1 so that an opening

- is formed to receive the hot coke falling from the retort just above. In the operation of discharging the carbonized material the sliding cover section Q^2 is first drawn out 5 the bottom stopper M is lowered and moved or swung off laterally and the carbonized material falls into the quenching vessel, whereupon the slide Q^2 is replaced and the steam generated in quenching passes up 10 through the central flue E to the stack R . Thus, the one central flue serves for carrying off the vapor or steam from the successive quenchings of the carbonized material from each of the retorts.
- 15 The retorts are heated by the burning of gaseous fuel in the combustion chambers or flues I, I', J, J' . The gas enters through pipes S and upright branch pipes leading therefrom, to the bottoms of the combustion 20 flues, being controlled by cocks or valves a, a' . At the bottoms of these combustion flues it is commingled with heated air entering in radial or other desired direction through lateral flues b, c from the bottoms of 25 the regenerating chambers K and L respectively.
- The tops of the regenerating chambers K, L are connected by flues d, e which unite in an upright flue f having a valve or cover 30 g and having a lateral branch entering into the base chambers of the stack R . The arrangement is such that when the regenerating chambers of (say) the odd-numbered sectors are drawing in air from outside, 35 their covers g being lifted (as shown at the left in Fig. 1), the regenerators of the even-numbered sectors are discharging the spent and cooled products of combustion through the flues d, e, f to the stack. This continues 40 for a suitable interval of time, whereupon the condition as respects the odd and even-numbered chambers is reversed. To accomplish this the upright pipes f, f' connect alternately into a lower and an upper stack 45 base chamber h, h' respectively, and provision is made whereby one or other of these base chambers is brought into communication with the stack R . For this purpose a suitable construction is that shown in Figs. 50 1, 4 and 5. The lower base chamber h is connected laterally with the upright flues f of the odd-numbered sectors while the upper chamber h' is connected with the flues of the even-numbered sectors. The chamber 55 h connects with the stack through a flue i controlled by a damper j . The chamber h' communicates with the stack through an opening i' controlled by a damper j' . The dampers j, j' are opened alternately. When 60 the damper j is closed the valves g of the odd-numbered flues f are open (as at the left in Fig. 1), and the valves g' of the even-numbered flues f are closed (as at the right in Fig. 1). When the damper j is 65 closed the damper j' is opened, and the
- relative positions of the odd and even-numbered valves g are reversed.
- Air to support combustion is admitted to the flues f which are opened by the lifting of their valves g , and descends through 70 flues d, e and through the regenerating chambers K, L , being heated by flowing around the hot baffle bricks or other obstructions in these chambers; the heated air then passes through the flues b, c and 75 supplies oxygen to the jets of gas admitted by the burners at the bottoms of the combustion flues I, J . The gases burn in these flues and heat the intervening retort H . The escape of the gases from the tops of the flues 80 I, J is more or less obstructed by top partitions k having perforations of either fixed or adjustable area, through which perforations the hot gases of combustion flow into upper connecting flues l, m . These 85 upper flues extend circumferentially for a distance covering two of the furnace sectors (as shown in the lower right-hand quadrant in Fig. 2, which is cut in the plane of these flues). Thus, the flues l, m 90 bridge over and connect respectively the combustion flues I, I' and the combustion flues J, J' of such two adjoining sectors.
- The burnt gases thus ascending from the flues I, J into the horizontal flues l, m are 95 conducted by the latter in circumferential direction over the tops of the flues I', J' ; the hot gases then descend through these flues, whereby they give up heat to the carbonizing retort H lying between them; 100 at the bottoms of these flues the hot gases pass through the flues b, c into the bottoms of the regenerating chambers K and L respectively. The gases then rise through these chambers, being diverted by the baffle 105 bricks or other obstructions therein, whereby they give up a considerable part of their remaining heat to these baffles; and finally the gases escape from the upper ends of these chambers through the flues d, e, f to 110 the stack (the valves g of the flues thus communicating being closed, and the valves j, j' so placed that these ascending products may enter the stack).
- It will be understood that the valves or 115 dampers j, j' and g, g' are manipulated at suitable intervals of time so as to reverse the flow of gases through the combustion flues I, J, I', J' , and regenerators K, L , these latter being alternately heated by the spent gases 120 of combustion and employed to deliver heat to the entering air. The alternation of the dampers must be effected at such intervals of time as will suffice, on the one hand, for heating up the baffles in the regenerating chambers, and, on the other hand, for effectively 125 heating the air which descends through these chambers.
- The coal or other carbonizable material is held in a bin or hopper T above the oven. 130

In order to charge the retort H the cap n closing the top of its flue N' is opened, and a hopper gate p directly over it is opened (any suitable chute being interposed if necessary), whereupon the coal or other material falls down through the flue N' into the retort until the latter is filled or sufficiently so; thereupon the gate p is closed and the cap n closed and fastened tight.

10 The quenching pan Q is closed at the bottom by a door q, by opening which the quenched coke may be dropped out (the water having been run out through this door or otherwise) and may be taken away by 15 any suitable receptacle, such as a conveyor working through a chamber or passage r beneath. In Fig. 1 a conveyor s is shown for this purpose. In order to avoid undue checking of the draft in the stack, the vapor 20 flue E may be closed when not in use by means of a damper such as the butterfly valve shown at t.

It may sometimes be found desirable to 25 adjust the areas of the flue ports or perforations in the partitions k. This may be accomplished by the means shown in Fig. 6 with respect to the flue l (or equally with the flue m). A loose tile or brick u is shown resting on the partition k, and which may be 30 pushed more or less over the perforation or port by means of any suitable rod or poker inserted into the flue l through the passage v which is normally closed by a removable cap w. Such a poker inserted for this purpose is shown in dotted lines at v'. The tile u may be variously constructed so that it 35 may be moved more or less by the poker, and the opening v may be of any suitable shape and size to permit of the necessary manipulation.

I have not deemed it necessary to illustrate in detail any means for operating the dampers j j' and valves g g, nor for lowering the retort doors or stoppers M M and moving 45 the latter sidewise to bring them out of line with the retorts and permit the gravity discharge of the coke; nor to show automatic means for operating the gas valves a a; various devices for these purposes being al- 50 ready known in the art and forming no part of my invention.

My invention is not limited to the precise means shown for controlling the inflow of air and the outflow of spent gases to the 55 stack. The flue connections, with their dampers j j' and valves g g, are shown as a simple and convenient construction which may be substituted by any other suitable means whereby during alternate phases of 60 the operation of the oven air may be admitted to the tops of the regenerators (for example) the odd-numbered sectors, and the spent combustion products from the tops of the intervening (even-numbered) regenerat- 65 ing chambers may be discharged to the stack.

In practice, with such ovens automatic devices are provided which reverse the flow through the regenerators at predetermined intervals of time (say, for example, 15 to 30 minutes), at the same time opening or closing the gas valves a a so as to admit gas only to those combustion chambers I J or I' J' in which the upward flow is occurring. Thus, the combustion flues or chambers I J and I' J' become alternately combustion 75 chambers in which the burning gases ascend, and heating flues in which the hot combustion products descend.

In the preferred use of the apparatus the retorts H H are emptied and recharged in 80 succession, either in their circumferential order or in any other order which may be found desirable. Thus, the carbonaceous charge in each retort is heated alternately by the burning ascending gases and by the hot 85 descending gases in its flanking chambers I J or I' J'. This heating is continued as many hours as may be necessary to complete the carbonization. During all this time the gaseous products distilled off are escaping 90 through the flues N N' to one or other of the hydraulic mains P P'.

In actual operation the gases thus distilled off, which may be combustible gases in the nature of illuminating, producer or 95 water gas, will be collected in any suitable gas holder. In the case of combustible gases, so much thereof as is required may be conducted to the gas supply pipes S for maintaining the combustion in the chambers 100 I J, I' J'. Water gas is produced by introducing steam to the retorts in the well-known manner. The kind of gas to be produced is dependent upon the way the operation is conducted, as is well known to those skilled 105 in the gas producing art.

Figs. 7, 8 and 9 show a simplified construction of the base of the stack. The chambers h h' are constructed and connected with the respective flues f in the same manner as in the construction first described, except that the vapor flue E is not carried up concentrically through the stack and through these chambers, but instead enters only the lower chamber h. This permits a 110 single damper j'' to be used in place of the two dampers j j'. When thrown to one side the lower chamber h is connected to the stack, and when thrown to the other side the upper chamber h' is so connected. This 115 construction operates the same as that first described, except that it is necessary during the quenching period that the damper j'' shall be thrown to the right, as shown, in order that the vapors may be drawn up the 120 stack.

The novel construction of carbonizing furnace herein set forth has certain important practical advantages. By reason of its upright, cylindrical or other equivalent form 125

and the consequent ease with which its walls, if of masonry, may be bound by hoops or otherwise, it has great structural stability. Its upright form also gives greatly increased 5 carbonizing capacity per unit of ground area occupied. The heat is generated and used interiorly, which secures the maximum avoidance of heat losses. The arrangement of regenerators on opposite sides of the retorts contributes to great economy by the 10 minimizing of heat losses. When used as a gas generator for carbonizing coal, the furnace permits of the carbonization of low volatile coals with a resultant product of 15 gas of very high quality, this being due to the more uniform temperature maintained, and to the fact that the retorts are vertical, which have been found in practice to give a higher quality and greater yield of gas and 20 by-products than with horizontal retorts. When used for the production of coke the same advantage in quality and quantity of gas is realized, and the resultant coke is of exceptional density, this being due to the 25 pressure exerted by the weight of the superimposed coal. The improved furnace permits of the use of coal of high volatility, and still results in a very dense coke. It has the advantage of vertical retorts in 30 avoiding the tendency of the charge to stick in place and resist the emptying of the retort. Because the gases distilled off from the coal or other carbonizable material are not as intimately brought into contact with 35 non-heat-absorbing incandescent surfaces, the formation and deposit of lamp black or other form of solid carbon is avoided and a greater quantity and value of by-products, such as tar, ammonia, benzol, etc., is realized. 40 By reason of the concentric arrangement the improved furnace permits of the convenient and compact central arrangement of a vapor flue or stack to carry off the steam produced during quenching. The new design permits 45 of the construction of carbonizing chambers and producer gas generators in relatively small plants, as it eliminates costly auxiliary apparatus such as a pusher for discharging the coke, a quenching car, and a coal-charging car. It affords the utmost economy in 50 labor as compared with other coke ovens, inasmuch as the work is done almost entirely by gravity. The gravity discharge of the coke renders unnecessary the employment 55 of any mechanical means such as pushers, and thereby eliminates the usual heavy maintenance charges on such coke-pushing equipment. Because of the vertical retorts with the quenching means directly beneath, the quenching of the coke is instantaneous, which avoids loss of coke by 60 combustion and also avoids the destruction of the vessels employed for carrying away flaming coke from the ovens. The new design 65 has also the advantage, when used as

a gas generator, of introducing steam during the entire carbonizing period, whereby to increase the production of ammonia from the coal.

The invention may be modified in many respects, as by the adoption of various expedients known to those skilled in the building of furnaces or ovens, and without departing from the essential features of the invention which are set forth in the claims which follow:

Although an upright cylinder affords the preferable form for the furnace, the invention is not limited thereto, as this form may be varied by the adoption of any equivalent upright figure of symmetrical cross-section; and the invention may be in part availed of by using one or more of the segments or sectors which constitute the elements which in their entirety make up the complete furnace in its preferred form.

I claim as my invention:

1. A carbonizing furnace formed as an upright structure having upright radial partitions dividing it into sectors, and circumferential partitions, the respective partitions forming upright segmento-annular carbonizing retorts of greater circumferential than radial dimension, open to the exterior at their bottom ends, with individual bottom closures therefor, upright segmento-annular combustion flues flanking such retorts, and upright segmento-annular regenerating chambers paralleling such combustion flues.

2. A carbonizing furnace comprising a walled structure formed of an annular series of segmento-annular upright carbonizing retorts, annular series of segmento-annular combustion flues flanking such retorts, and annular series of regenerating chambers, with connecting flues and gas inlets, and controlling means adapted to alternately admit heated air and gas to the combustion flues and discharge hot products of combustion therefrom through the regenerators.

3. A carbonizing furnace formed as an upright structure of approximately cylindrical form having an annular series of carbonizing retorts each flanged by combustion flues and regenerating chambers, the oven having to each pair of retorts flues connecting the upper ends of their combustion flues, and flues connecting their lower ends with the regenerating chambers, and flues connecting the upper ends of the regenerating chambers with a stack, gas inlets, and controlling means for said flues and inlets whereby the regenerators are alternately heated by the escaping spent gases and employed to heat the air admitted for maintaining combustion in said combustion flues.

4. A carbonizing furnace formed as an upright cylinder subdivided to constitute a concentric annular series of carbonizing retorts and heating flues flanking such retorts,

with a quenching vessel beneath the furnace adapted to receive the carbonized material discharged from any one of the retorts, and with a vapor flue leading from said quenching vessel up through the center of the furnace.

5. In a carbonizing furnace, segmento-annular upright retorts, a pair of upright segmento-annular combustion flues flanking 10 said retorts and upright regenerating chambers communicating with said flues at one end, and flues connecting the pair of combustion flues at the other end thereof; with gas inlets to said combustion flues, and means 15 for controlling said inlets and for controlling the direction of flow through said pair of flues and regenerating chambers.

6. In a carbonizing furnace, upright segmento-annular carbonizing retorts, a pair 20 of segmento-annular combustion flues paralleling said retorts and regenerating chambers communicating with said flues at their bottoms, and flues connecting the pair of combustion flues at their tops, gas inlets to 25 the bottoms of the combustion flues, and means for controlling said inlets and for controlling the flow through said flues and regenerating chambers.

7. In a carbonizing furnace, upright segmento-annular retorts, a pair of upright 30 combustion flues closely paralleling said retorts, a pair of segmento-annular regenerating chambers communicating with said pair of flues respectively at one end, and a horizontal flue connecting the combustion flues 35 of such pair at the other end thereof; with gas inlets to said combustion flues, flues leading from the regenerating chambers, valves controlling the admission of air to said latter flues, a stack, and connections from said latter flues to the stack, and means for controlling said flues and gas inlets, whereby air is admitted through a regenerating 40 chamber to a combustion flue for one retort, through which flue the burning gases pass, and thence to and through the next combustion flue and then pass through the other regenerating chamber to the stack, such flow being reversible from time to 45 50 time.

8. In a carbonizing furnace, an upright structure divided to form a co-centric arrangement of successive upright carbonizing retorts each flanked by heating flues, charging flues at the upper ends of said retorts through which to introduce carbonizable material, a hopper for such material above the furnace having gates for discharging the material directly into the respective charging flues, individual bottom stoppers for the bottoms of the respective retorts, and a quenching tank beneath the furnace adapted to receive directly the carbonized material discharged from either of said retorts, whereby the furnace is adapted for continu-

ous carbonizing in said retorts by discharging and recharging them in succession.

9. In a carbonizing furnace having a plurality of sections, each section including an upright segmento-annular carbonizing 70 retort, with combustion flues flanking it and regenerators adjacent said flues, the successive retorts forming an annular series, and the successive regenerators forming an annular series, and a stack above the furnace 75 having at its base two chambers, flues connecting from the regenerators to said chambers, the flues from the odd-numbered regenerators to one chamber and from the even-numbered regenerators to the other 80 chamber, and means for connecting either stack chamber to the stack whereby to draw products of combustion from the even-numbered or odd-numbered regenerators and their connected combustion flues at will. 85

10. A carbonizing furnace formed as an upright structure of approximately cylindrical shape subdivided by upright circumferential partitions and upright radial partitions to form a plurality of upright carbonizing retorts arranged in a co-centric annular series, two series of co-centric heating flues flanking such retorts, the one series arranged annularly exteriorly of the retorts and the other series arranged annularly interiorly of the retorts, and regenerating chambers parallel to such flues and arranged respectively exteriorly and interiorly of the retorts.

11. A carbonizing furnace formed as an upright structure of approximately cylindrical shape subdivided by upright circumferential partitions and upright radial partitions to form a plurality of upright carbonizing retorts arranged in a co-centric 100 annular series, two series of heating flues flanking such retorts, the one series arranged annularly exteriorly of the retorts and the other series arranged annularly interiorly of the retorts, and two series of regenerating chambers paralleling said flues, 105 the one series exterior to the outer heating flues and the other series within the inner heating flues. 110

12. A carbonizing furnace formed as an upright structure subdivided by upright partitions to form a central vertical flue, a series of segmental regenerating chambers surrounding such flue, an annular series of combustion flues surrounding such chambers, an annular series of upright carbonizing retorts surrounding said flues, a second series of combustion flues surrounding said retorts, and an outer annular series of regenerating chambers surrounding said last-named flues. 115 120 125

13. A carbonizing furnace formed as an upright structure subdivided to form upright carbonizing retorts and combustion flues, and a central flue passing entirely 130

- through the structure, with a stack mounted on top of said structure communicating with said central flue and connected to create a draft through said combustion flues.
5. 14. A carbonizing furnace formed as an upright structure subdivided to form upright carbonizing retorts and combustion flues, and a central flue passing entirely through the structure, a quenching tank beneath said structure adapted to receive directly the carbonized material discharged from any of said retorts, a connection from said tank to the bottom of said central flue, and a stack above said structure connected 10 to the top of said central flue to create a draft for drawing off vapors from said tank.
15. A carbonizing furnace formed as an upright approximately cylindrical structure subdivided by vertical partitions to form a plurality of upright carbonizing retorts having bottom openings, and upright combustion flues flanking such retorts, and a central flue passing vertically through said structure, a framework supporting said structure, 20 a quenching tank located centrally beneath said structure to receive the carbonized material discharged from any of said retorts and connected with the bottom of said central flue, and segmental covers for said quenching tank corresponding to such retorts, whereby when a retort is to be discharged the segmental cover beneath such retort may be withdrawn without otherwise uncovering the quenching tank.
16. A carbonizing furnace formed as an elevated upright structure subdivided to form a group of upright carbonizing retorts, with heating flues adjacent to such retorts, the several retorts open at their bottom ends to discharge downwardly by gravity, independent individual closures for the bottoms of the respective retorts, a quenching vessel beneath the furnace adapted to receive the material discharged from any of the retorts, and means for covering said vessel adapted to be opened beneath any one retort when discharging carbonized material 40 therefrom into said vessel.
- In witness whereof, I have hereunto signed my name.

GEORGE A. BAIZ.
